(57) **CLAIM**

The ornamental design for an ink pack, as shown and described.

DESCRIPTION

FIG. 1 is a front, top and right side perspective view of an ink pack showing our new design;

FIG. 2 is a front, bottom and left side perspective view thereof;

FIG. 3 is a rear, top and left side perspective view thereof; FIG. 4 is a rear, bottom and right side perspective view thereof;

FIG. 5 is a front view thereof;

FIG. 6 is a rear view thereof;

FIG. 7 is a top plan view thereof;

FIG. 8 is a bottom plan view thereof;

FIG. 9 is a right side view thereof;

FIG. 10 is a left side view thereof;

FIG. 11 is an enlarged view of a portion defined by lines 11-11 in FIG. 1;

FIG. 12 is an enlarged view of a portion defined by lines 12-12 in FIG. 2;

FIG. 13 is an enlarged view of a portion defined by lines 13-13 in FIG. 3; and,

FIG. 14 is an enlarged view of a portion defined by lines 14-14 in FIG. 4.

The dash-dash broken lines illustrate portions of the ink pack that form no part of the claimed design. The dash-dot-dash broken lines represent the bounds of the enlarged views and form no part of the claimed design.

1 Claim, 14 Drawing Sheets
